UNITED STATES PATENT OFFICE.

ALFRED BRYANT FISHER, OF NEW YORK, N. Y.

POLISHING COMPOSITION.

No Drawing.

Application filed April 14, 1924. Serial No. 706,560.

This invention relates to a polishing composition.

An object of the invention is to provide a polishing composition in which the ingredients are so finely divided and so particularly selected that they are specially adapted for polishing and graining metal surfaces and far superior for this purpose to any of the hitherto known compositions.

Another object concerns the provision of a composition which can be very cheaply made and readily presented on the market in various forms, either as a dust or granular mass in boxes or compressed in the form of sticks or cakes.

A further object concerns the provision of a composition which is especially useful to photo-engravers for the purpose of polishing and graining zinc and copper plates.

When the photo-engravers receive zinc and copper plates from the manufacturers these plates are cut up into smaller plates and in most cases ordinary powdered pumice is rubbed over the surface with a pad of felt, absorbent cotton, or even cloth under running water. This rubbing continues until the surface of the plate is finely grained. Other engravers may use charcoal, which removes surface grease, and also gives

a fine tooth or grain to the metal. The whole idea of polishing the plates with pumice is to give them a fine tooth so that the chemicals with which they are treated more readily cling to the surface of the

metal. Charcoal is principally used by the engravers on copper plates, because high class half-tones are generally done on copper and a slight scratch on the surface would show through the enamel when printed.

Charcoal is also used on copper because the copper is very hard and charcoal cuts it better than pumice. My compound is intended to replace the charcoal for use in treating copper plates as well as zinc plates.

My principal idea in developing the composition on which I desire to obtain a patent is to have it replace pumice as ordinarily used, as it will do the work better and quicker.

My composition in general comprises very finely divided or ground metal dust, very

finely grounded pumice, and a small quantity of oil. Sometimes I find it desirable to provide the composition with small quantities of fine particles of felt or fibrous material. The metal dust provided in the composition may be zinc, copper or any other desirable metal. Preferably the metal dust for any particular polishing composition is the dust of the metal the plates of which the composition is intended to polish or grind. For instance, if we sell the composition for polishing copper plates, then the metal dust in this form of the composition will be a fine copper dust; whereas if we sell the composition for the purpose of grinding or polishing zinc plates, then the metal dust is finely divided zinc dust.

Preferably the percentage of metal dust in the composition will run between ten and twenty per cent, being largely finely ground pumice and a small percentage of oil, and in some cases a small percentage of finely divided felt or fibrous material. The oil gives the mixture the proper greasiness and acts as a sort of binder to intimately incorporate the various ingredients together.

These ingredients may be subjected to pressure to form sticks or blocks or cakes, in which case a small quantity of lard or fat is added to act as an additional binder.

The most important feature of this composition, aside from the particular ingredients used, is the fineness to which the metal dust, the pumice and the fiber are ground.

The particular composition will do the polishing or grinding work for the engravers much better and quicker than straight pumice because the use of powdered zinc against zinc plates and powdered copper against copper plates makes a wonderful abrasive. The great difficulty that photo engraving plants encounter in the purchase of pumice is that they cannot get very finely ground pumice, and the kind they usually obtain is very poorly graded and scratches their plates. The variableness of the quality of the pumice obtained causes considerable trouble. By reason of the fact that this composition is ground to exceeding fineness and varies only to a small extent within certain limits, the character of the polish-

ing composition can be regulated so that a standard, uniform product is available for the buyers.

What I claim is:

5. 1. A polishing composition, which comprises an intimate mixture of finely divided metal dust, pumice and oil.
2. A polishing composition, which comprises and intimate mixture of ten to twenty
10 per cent finely divided metal dust and pumice.
3. A polishing composition, which comprises an intimate mixture of very finely

divided metal dust, pumice, oil and fibrous material.

15

4. A polishing composition, which comprises an intimate mixture of finely divided zinc dust, pumice and oil.

5. A polishing composition which comprises an intimate mixture of very finely divided metal dust, pumice and oil, the metal dust being ten to twenty per cent of the bulk while the oil is sufficient to cause the bulk to be a paste.

ALFRED BRYANT FISHER.
